ATTORNEY

UNITED STATES PATENT OFFICE.

EDWIN B. STIMPSON, OF BROOKLYN, NEW YORK.

LOCKING DEVICE FOR USE IN PUNCHING-MACHINES OR THE LIKE.

SPECIFICATION forming part of Letters Patent No. 703,747, dated July 1, 1902.

Application filed January 14, 1902. Serial No. 89,734. (No model.)

To all whom it may concern.

Be it known that I, EDWIN B. STIMPSON, a citizen of the United States, residing in the borough of Brooklyn, county of Kings, and city and State of New York, have invented 5 certain Improvements in Locking Devices for Use in Punching-Machines or the Like, of which the following is a specification.

This invention is especially well adapted to 10 a gang punching-machine of the kind illustrated in my United States Patent No. 665,702, of January 8, 1901; and it has been found convenient to illustrate the invention in connection with such a machine, although its 15 application and use is not necessarily limited to a punching-machine of this character, but may be employed in many cases where a shiftable part is to be secured in place after adjustment. It may be stated here briefly 20 that in my said patent a multiple or gang punching-machine is described which has a plurality of punching devices arranged abreast and capable of being spaced and locked in position after adjustment by means 25 fully described therein, the parts included in each set being locked simultaneously.

In the present case the invention resides in the means for locking independently each 30 element of the punching devices, whereby the construction of the machine is much simplified and cheapened.

In the accompanying drawings, Figure 1 is a front elevation of the machine, and Fig. 2 is a vertical section of the same at the line 35 x^2 in Fig. 1. Fig. 3 is an end view of one of the dies or die-blocks detached; and Fig. 4 is a section of same *in situ* at line x^4 in Fig. 3. Fig. 5 is a sectional view at line x^5 in Fig. 6, showing the locking device for the punching 40 guide; and Fig. 6 is a section at right angles to that of Fig. 5. In these last two views the locking-jaw and screw are seen in elevation.

1 designates the main frame, 2 the bed or 45 table thereon, and 3 an upright frame on the bed upon which slides the head 4, which carries the punches. This head is coupled by links 5 to the straps of eccentrics 6 on the driving-shaft 7, mounted in the frame below. 50 8 is the driving-pulley, adapted to be connected by a clutch device 9 to the shaft 7 for driving, and 10 is a treadle by which the

operator sets the punching-machine in operation.

Mounted on the head 4, so as to be slidable 55 therealong transversely of the machine for spacing and also from front to rear for convenience in placing and removing the punches 11, are punch holders or carriers 12, and mounted slidably on a fixed bar 13 on the table or bed 2 are punch-guides 14, movable along the bar 13 for spacing to correspond with the punches. In a slotted member or portion 2^a of the bed 2 are mounted slidably the die-blocks 15. The die-block may have 65 the die formed in it, or a die 16 may be set therein, as shown in Fig. 4. This matter of the separate construction of the die is not important to the present invention.

Substantially all of the features described 70 above are in my Patent No. 665,702, before mentioned, and in said patent means are shown for securing after adjustment the entire set or series of die-blocks and punch-guides, and the present invention relates to 75 an improvement thereon. This feature will now be described with especial reference to Figs. 3 and 4 for the application of same to the die-block and Figs. 5 and 6 for the application of same to the punch-guide. 80

The die-block 15 rests in the slot in the member 2^a and is supported on shoulders at 2^b therein. It is a loose fit in the slot, so that when unclamped or unlocked it may be moved freely along the slot. In order to lock or secure the die-block in position in the slot when properly adjusted or set, it is provided with a locking-jaw 17 in the nature of a plate, which fits in a gain in the end of the block and has a stem 18, guided in a bore in the 90 block. This stem has a notch formed in it, and the side or wall 19 of the notch next to the jaw 17 is inclined. A screw 20 with a conical tip is driven through the side of the block at right angles to the axis of the stem 95 18 and in position for the conical tip thereon to bear on the incline 19, and thus wedge or drive outward the jaw 17 and cause it to press against the wall of the retaining-slot, as seen in Fig. 4. This practically lengthens the 100 block and locks it securely in the position to which it may have been adjusted. By withdrawing the screw 20 the block is freed and may be shifted along the slot at will.

Figs. 5 and 6 illustrate the application of the same invention to the clamping or locking of the punch-guide 14 to the dovetail 13^a on the bar 13, along which the punch-guide 5 is shifted. This construction is precisely the same as that shown in Figs. 3 and 4, except that the face of the locking-jaw is beveled to correspond with the bevel of the dovetail strip 13^a on the bar 13. Obviously in any 10 case the face of the jaw will have the proper inclination or bevel to fit to the surface it is to bear on. It will be noted that this means for locking the part is confined to the individual part, and thus either set may be shifted 15 and locked or secured while the other sets are still free, and this is an important advantage in preparing the machine for punching; or it may be, for example, desirable to adjust or shift but one set of the punching devices— 20 that is, a holder 12, a guide 14, and a die-block 15—leaving the other sets fast, and this means of securing the parts permits of this. The punch-holder 12 need not be secured.

It should be understood that in a gang 25 punching-machine of this character there is a plurality of punching devices, each device comprising a set of parts or elements—namely, a punch-holder, a punch-guide, and a die-block. All of the sets are alike, and all 30 of the corresponding elements of the sets are alike in substance—that is, all the holders are alike, all the guides are alike, and all the die-blocks are alike. The latter are alined by being pressed in locking or clamping up 35 to the front wall of the slot in the table or bed.

It will be noted that with the construction shown the jaw or plate 17 is moved in a direction at right angles to the direction in which the pressure is applied in driving the screw 40 20. This enables the screw to be reached with facility as the upper surface of the die-block is exposed. The jaw or plate 17 may have any suitable contour.

It will be understood that the device above 45 is not a means for permanently securing a part to another in the manner of drawboring to secure a tenon in a mortise nor as a means for operating a wedge. It comprises, essentially, a guided stem provided with a clamp- 50 ing jaw or head, the face of which is disposed at right angles to the line of movement in clamping or applied directly by the pressure. The function of the screw is merely to transform the applied pressure at right angles, so 55 as to facilitate access to the screw. The locking device is mounted in the movable part or element to be locked, so that this part can be secured at any point to which it may be shifted or adjusted.

Having thus described my invention, I do claim—

1. In a machine of the character described having a support for the same, a movable part or element to be secured in place on said support, said element having mounted in it a locking device to secure it in place on the machine, said locking device comprising a jaw having a stem provided with a bearing in the element, and a screw driven into said element in a direction transversely to the axis of said stem, the said stem having on it a shoulder in position to be impinged upon by the conical tip of said screw for moving the stem longitudinally, the clamping-face of the jaw being on the side of the same opposite to the stem thereof, substantially as set forth. 65 70 75

2. In a machine of the character described having a support for the same, a movable part or element to be secured in place on said support, said element having mounted in it a locking device to secure it in place on the machine, such locking device comprising a jaw in the nature of a plate which normally occupies a recess in the surface of the element, a stem on said jaw which extends into the body 85 of the element, and which is provided with an inclined shoulder, and a cone-pointed screw which screws into said element in position to apply the conical surface of its point to the inclined shoulder on the stem to drive 90 the jaw out from its recess, substantially as and for the purpose set forth.

3. The combination with a machine-bed having in it a slot and suitable supporting-shoulders, and a die-block supported on said shoulders and movable along said slot between the walls of the same, of a locking device carried by said block for locking it in position in the slot when adjusted, said locking device comprising a clamping-jaw 17, occupying a recess in the end of the die-block adjacent to the side wall of the slot in the bed, the shank 18, of said jaw, which shank extends into the block and has on it a shoulder, and the cone-pointed screw 20, driven in the block transversely to the axis of said stem and in position to bear on the shoulder on the latter and thus drive the jaw forcibly outward and against the side wall of the containing-slot in the machine-bed, substantially as set forth. 100 105 110

In witness whereof I have hereunto signed my name, this 7th day of January, 1902, in the presence of two subscribing witnesses.

EDWIN B. STIMPSON.
